CLAIM

The ornamental design for a display screen or portion thereof with a graphical user interface, as shown and described.

DESCRIPTION

The FIGURE is a front view of a display screen or portion thereof with a graphical user interface showing our new design;

The broken lines in the FIGURE show portions of the display screen or portion thereof with a graphical user interface which form no part of the claimed design.

The dash-dot broken lines shown in the FIGURE represent boundaries of the claimed design.

The graphical images shown within the dash-dot boundary lines form no part of the claimed design.
